(57) **CLAIM**

The ornamental design for heart jewelry, as shown and described.

DESCRIPTION

FIG. 1 is a perspective illustration of a heart design element and associated jewelry according to the new design.

FIG. 2 is a front plan view thereof.

FIG. 3 is a rear plan view.

FIG. 4 is an elevation view from below in FIG. 2.

FIG. 5 is an elevation view from above in FIG. 2.

FIG. 6 is a side elevation from the right in FIG. 2; and, FIG. 7 is a side elevation from the left in FIG. 2.

The broken lines in the drawings represent environmental matter and form no part of the claimed design.
